John Templeman
Setton's Patent

Issued Aug. 16. 1863.

The structure referred to in these Setton's Patent and marking place of the same containing a description in the words of the said John Templeman himself of his improvements and applications to his new Chain Bridge.

Improvement the first. When the piers to be used for the piers for the chains and the uprights shall stand in the situations in the manner as described by the above patent and let them rest in the middle of the river, in the river without any upright, hang the chains at first within 12 to 15 inches of the top of the pier, and when the bridge is floated block up to it with square timber till it takes a proper bearing. Go on with the suspender and posts as are directed by the above patent and extend the floor from one abutment to the other. In this case the upright will require to be higher than in Judge's single plan improvement the second. Then it may be preferred to an upright in the pier instead of the foregoing; in that the pier must be constructed in such a way as to have strength enough to support the weight of a skeleton, may be an open while the opposite pier has nothing on it, in such cases great strength and perfect stability are indispensably necessary. Then a pier can be built in from material rock from four to six tons of iron & timber, rods and wedges are to be planted firmly in the natural rock, and at the distance of every four to five feet of such square, must be made through the flat bars and bars of rock, square iron 4 feet long are to be run through them in such a manner as to take a strong ^{square} hole of the ^{square} iron inside of them. Then flat bars of iron are to extend up and come out at the top of the pier about two feet and then pass through the bars of the upright and then driven in such a manner as to bind the upright to the pier, in a more forcible way. Now the pier there is to be a hole in the head of the bars of iron such a place from whom a chain a bar of iron is to be extended up to the arms of the opposite. Besides these forcible supports to the upright there are bars of flat iron to come up the sides of the pier and bolt to the bars of the upright under the middle of the

building of the bridge. Since there is also of course a further power intended by me for this purpose, that is to plant the ends of the iron bars in the natural rock and carry the bars up the river and to the top of the upright and then down the cap piece and down on the opposite sides and fasten the ends to the natural rock setting and picking as you go. This of course, which is intended to support an upright which upright is to support the span, is to be built in a line of granite bottom bars of iron or strong timber are to be laid across at bottom of the river, lay an inch and a half upon each iron and the last long timber the flat bars are to be attached, but if the bottom should be hard and it becomes necessary to build the river bank, then the iron and bars are to be built back to the bank, the iron either in bars or chains are to be attached to the river at the bottom of the bank and then brought up a short distance and made fast to the flat bars which are to continue up the sides of the river and then are to be fastened to the timber to serve the double purpose of strength to the river and supports. The ends of the bars in this case will go up on the outside of the upright and fast to it, but care must be taken to have the chains from the ends of the cap pieces connect with these bars. My uprights are covered with white marble and will answer the intended purpose of protecting the timber in the river longer than without it, or, besides the above advantages of strength, I have invented a way to apply whale and Bruce chains to help the stone chain bridge more strongly, and floors more solid as well as to give it sufficient additional strength to the uprights and as the bridges that are now built on the stone principles seem to be much complained of for want of stability I have applied the first and last to what some call the King post principle with the railings which while it affords great additional stability to the floor also affords great support to the chains by depressing the upright and equalizing it. Besides the above mentioned improvements and application I have invented an entire stone chain bridge with a method of suspending ropes or cables of hemp or of iron, which fast into blocks and then at right and then into cable or iron chain stop ways. The ropes of this are intended to counteract or avoid the effect of frost on the chains as it is possible that in very cold climates the frost may break the chain ropes. The iron ropes are to be well oiled and covered with tar. Cloth and

related with spun yarn and at the distance of every 8 or ten feet they are to have two pieces of iron of six inches long and half an inch thick riveted to it at the time of laying, the rope to keep the suspension at proper distances. The principle of cross ropes or chains will oppose a more solid and steady force than the cross chains do and will be much less troublesome to lay. And next this principle in laying and suspending an upright on a chain that have to resist the weight of the front and to support itself against one another will be, provide in the bottom, to it, at least one and half inches, two chains to be secured with links of one bar and not as here mentioned, with two bars. In the formation of a stone chain Bridge with stone piers secured also are to be secured in bridge trusses, placed at an angle, and that is to have the upright higher in proportion to the length of the pier and not let the lower part of the stone chain between the uprights of the trusses to a stone. But to let the lower part in middle of the stone uprights in the top of the top of the Pier and about seven and even then let the stone chain 10 or 12 inches in the middle and about, firmly against the stone truss to stand. This and in this state the stone chains that are extended from the middle of the big chains to the extremities of Pier will operate in a reciprocal manner to support the middle upright.
